OTTO ACKERMANN, OF WILKINSBURG, PENNSYLVANIA, ASSIGNOR TO WESTINGHOUSE ELECTRIC & MANUFACTURING COMPANY, A CORPORATION OF PENNSYLVANIA

CATHODE-RAY OSCILLOGRAPH

Application filed June 22, 1929. Serial No. 373,043.

My invention relates to cathode-ray oscillographs and particularly to apparatus for moving the electron beam of an oscillograph of the aforesaid type along a time axis. 6 In order to obtain a voltage-time record with a cathode-ray oscillograph, either the recording surface or the electron beam must be moved along a time axis. This movement may be a continuous one independent 10 of the phenomenon to be recorded (as is the case when either a rotating film drum or an oscillatory voltage continuously impressed on the timing plates is employed) or it may be initiated shortly before, or at the beginning 15 of, the occurrence of the phenomenon to be recorded. In many respects, the second method of obtaining a time movement is superior to the first. My invention resides in improvements in the apparatus for initiating a timing movement in accordance with the second-named method.

An object of my invention is to provide, in apparatus of the above mentioned type, means for initiating the timing movement 25 of the electron beam in response to the occurrence of a surge or other electrical phenomenon to be recorded.

A further object of my invention is to provide apparatus of the above mentioned type 30 so designed that, when permanently connected to a transmission line, a surge, occurring on the line, will impress the electron beam against the recording surface and simultaneously cause a varying voltage of known characteristics to be impressed on the oscillograph timing plates.

The relay structure, which includes two sets of deflecting plates for bending an electron beam around a target positioned therebetween, is described and claimed in U. S. 40 applications S. N. 238,505 and S. N. 296,844 filed in the name of E. H. Norinder on Dec. 8, 1927 and Aug. 1, 1928, respectively, such applications having been assigned to Westinghouse Electric & Manufacturing Company.

In practicing my invention, I employ an evacuated vessel containing a pair of electrostatic deflecting plates, a target and means 50 for normally projecting a beam of electrons

against the target. A resistance unit, having a condenser and a pair of oscillograph timing plates connected in parallel therewith, is connected between the target and ground so that, until the electron beam is deflected, 55 the condenser is charged to a constant potential by the flow of electrons or current from the target to ground. The instant that the electron beam is deflected away from the target, the condenser begins to discharge 60 through the resistance unit, and the voltage impressed across the timing plates is decreased at a known rate.

Other features and advantages of my invention will appear from the following description, taken in connection with the accompanying drawing, in which

Fig. 1 is a sectional and diagrammatic view of the apparatus and electrical connections employed in one embodiment of my 70 invention;

Fig. 2, is a view, similar to that of Fig. 1, of the apparatus employed in another embodiment of my invention and of the electrical connections employed therewith; 75

Fig. 3, is a view, in longitudinal section, taken on line III—III of Fig. 2;

Fig. 4, is a view, in lateral section, taken on line IV—IV of Fig. 2.

Referring to Fig. 1, the apparatus comprises an evacuated glass vessel 1 having means in the upper end thereof for generating a beam of electrons. The electron-beam-generating means comprises a cathode 2 of the filament type, which is heated by means of a battery 3, and an anode 4 having an aperture therein positioned below the cathode 2 and supported by means of a metal rod 5 sealed into the wall of the glass vessel 1. Some suitable source of high direct-current potential 6 is connected between the cathode 2 and the anode 4. 80

A metal target 7 is positioned in the lower end of the evacuated vessel 1 in alignment with the cathode 2 and an aperture in the anode 4. A metal screen 8, having an aperture therein, is supported by means of a metal rod 9 sealed in the side walls of the glass vessel 1, with the aperture directly 95 100

above the target 7. The screen is preferably grounded.

Electrostatic deflecting plates 10 of metal are supported by means of metal rods 11 sealed in the side walls of the glass vessel 1 and are positioned between the anode 4 and the target 7. One deflecting plate 10 is connected to ground. The other deflecting plate 10 is connected to a point on an electrostatic 10 potentiometer 12. The potentiometer 12 comprises a plurality of condensers 13 connected in series between a transmission line 14 and ground.

The target 7 is connected to ground through 15 a resistance unit 15 which has the electrostatic timing plates 16 of a cathode-ray oscillograph (not shown) connected in parallel therewith. Unless the capacity between the timing plates 16 is sufficient, a condenser 17 20 is connected in parallel with the resistance unit 15.

In operation, so long as there is only a normal voltage on the transmission line 14, the beam of electrons will be projected from the 25 opening in the anode 4 against the target 7. These electrons will then be conducted to ground through the resistance unit 15. This flow of electrons or current will maintain a constant potential across the timing plates 30 16 and across the condenser 17 to keep the condenser and the timing plates (which also act as a condenser) charged to a fixed degree. As soon as a surge or an unusually high voltage appears on the transmission line 14, the 35 electron beam will be deflected sufficiently by the deflecting plates 10 to move the beam off the target 7 and against the screen 8. This interrupts the flow of electrons through the resistance unit 15, and the capacity units 16 40 and 17 immediately begin to discharge therethrough, thus lowering the voltage impressed across the timing plates 16. Since the rate of discharge is known, a known timing movement is imparted to the electron beam of the cathode-ray oscillograph.

Instead of comprising a separate evacuated vessel, as described in connection with Fig. 1, the structure for initiating the timing movement may be combined with the cathode-ray oscillograph itself, as shown in Figs. 50 2 to 4.

Referring to Figs. 2, 3, and 4, the apparatus comprises a metal envelope 20, at the lower end of which is supported a metal casing 55 or chamber 21 in which a suitable photographic plate or film 22 may be placed.

The upper end of the envelope 20 is closed by means of a plug 23 having a tube 24 of insulating material, such as glass, secured 60 thereto and projecting axially from said envelope. The upper end of the tube 24 is provided with a cap 25 centrally apertured to permit the passage therethrough of the terminal 26 of a cathode 27. The cathode terminal 26 is enlarged at 28 to completely close

the aperture in the cap 25. A suitable sealing compound may be employed to secure the several elements together. Preferably, a cold cathode is employed, but, obviously, a hot cathode may be employed if desired.

An anode 29 is supported at the lower end 70 of the glass tube 24 and is provided with an axial aperture so that the beam of electrons from the cathode to the anode will pass therethrough.

A frame, which is supported inside the metal envelope 20, consists of four rods 30 supported at their respective ends and at a point intermediate their ends by rings 31. The rods 30 are preferably of metal in order 75 to make a strong frame but they may be of insulating material.

Metal deflecting plates 32 are secured to the rods 30 near the upper end of the frame. The plates 32 are insulated from the rods 30 80 and are connected to terminals 33 that lead through insulating bushings in the metal plugs 34 to the outside of the metal tube 20.

Near the middle of the frame and suitably secured thereto and insulated therefrom, other deflecting plates 35 are supported in parallel relation to the upper deflecting plates 32. The left-hand plate of the lower pair of plates 35 is connected to the right-hand plate of the upper pair of plates 32. Likewise, the right-hand plate of the lower pair of plates 35 is connected to the left-hand plate of the upper pair of plates 32.

A target or shield 36 is supported between the two sets of deflecting plates. The target 100 36 comprises a strip of metal 36 eccentrically mounted on a metal plug 37 which is set into the wall of the casing 20. By rotating the plug 37, the target 36 may be positioned directly in the path of the undeflected electron beam. Since the casing 20 is ordinarily grounded, the target should be insulated from the plug 37 and connected to a terminal rod 38 extending through an insulating bushing in the plug 37.

Below the second pair of deflecting plates 35 is a screen or diaphragm 39 mounted on the rods 30. This screen is preferably of metal and need not be insulated from the supporting rods 30. The screen is provided 115 with a central opening 40, the diameter of which is approximately the same as the width of the target 36.

A pair of deflecting or timing plates 41 are mounted on the rods 30 below the screen 39 and insulated therefrom. The timing plates 41 are positioned at right angles to the upper deflecting plates 32 and 35, as is well understood in the art, in order to give the electron beam a timing movement transverse 120 to the movement caused by the upper deflecting plates 32 and 35. As is more clearly shown in Fig. 4, the timing plates 41 are 125 mounted on the rods 30 by means of supporting members 42 and are connecting to termi- 130

nal rods 43 by means of conductors 44. It will be noted that two of the rods 30 have been bent around the conductors 44.

A suitable source of high direct-current potential 45 is connected between the cathode 27 and the anode 29. The two deflecting plates, which are connected together by means of the conductor 46, are connected to a point on an electrostatic potentiometer 47 which is connected between a transmission line 48 and ground. The other two deflecting plates 32 and 35 are connected to ground. The target 36 is connected to ground through a resistance unit 49 which, preferably, has a condenser 50 connected in parallel therewith. One timing plate is connected to the upper end of the resistance unit, while the other timing plate is connected to ground.

In operation, a negative voltage is impressed upon the cathode 27 which results in an electron beam shooting through the anode 29 against the target 36. The voltage to be measured is then impressed upon the deflecting plates 32 and 35. In the example illustrated, this voltage is a voltage surge which occurs on the transmission line 48, as the result of some chance disturbance, such as a stroke of lightning. The upper pair of deflecting plates 32 will so deflect the beam that it will pass to one side of the target 36. The beam will then pass between the second pair of deflecting plates 35 and be deflected by them in a direction opposite to the first deflection, as indicated by the dotted line 51 in Fig. 2. The deflected beam will then pass through the hole in the shield 39 and between the timing plates 41 and be intercepted by the photographic plate 22. The deflecting plates 32 and 35 and the screen 39 are so adjusted with respect to each other that the electron beam will pass through the aperture in the screen 39 after it is deflected past the target 36, no matter what the angle of deflection may be.

The angle which the deflected beam makes with respect to the longitudinal axis of the tube 20 depends upon the value of the voltage impressed upon the deflecting plates 32 and 35. Therefore, the amount which the beam is deflected, as recorded on the photographic plate 22, is a measure of the voltage impressed upon the deflecting plates.

Since a stationary photographic plate is employed, it is necessary to employ the timing plates 41, as is well understood in the art. It will be seen that, as soon as the electron beam is deflected away from the target 36, the flow of current through the resistance unit 49 is interrupted, and the condenser 50 discharges therethrough, as described in connection with Fig. 1. Consequently when a surge occurs on the transmission line 48 the electron beam is projected against the photographic plate 22 and, at the same time a varying

voltage of known characteristics is impressed upon the timing plates 41.

Various modifications may be made in my invention without departing from the spirit and scope thereof and I desire, therefore, that only such limitations shall be placed thereon as are shown by the prior art and are set forth in the appended claims.

I claim as my invention:

1. Electrical apparatus comprising a target, means for generating a beam of charged particles and for projecting said beam against said target, means for deflecting said beam away from said target, an impedance unit, means for conducting said charged particles away from said target through said unit and means responsive to the voltage drop across said impedance unit for deflecting a beam of charged particles.

2. Electrical apparatus comprising a target, means for generating a beam of charged particles and for projecting said beam against said target, an impedance unit, means for conducting said charged particles away from said target through said unit and a pair of electrostatic deflecting plates connected across said impedance unit.

3. Electrical apparatus comprising a target, means for generating a beam of charged particles and for projecting said beam against said target, a resistance unit, means for conducting said charged particles away from said target through said unit and a pair of electrostatic deflecting plates connected across said resistance unit.

4. Electrical apparatus comprising a target, means for generating a beam of charged particles and for projecting said beam against said target, a resistance unit, means for conducting said charged particles away from said target through said unit and a condenser and a pair of electrostatic deflecting plates connected across said resistance unit.

5. Electrical apparatus comprising a target, means for generating a beam of charged particles and for projecting said beam against said target, means for deflecting said beam away from said target, an impedance unit, means for conducting said charged particles away from said target through said unit, a cathode-ray oscilloscope including timing plates and means for electrically connecting said timing plates to a point on said impedance.

6. Electrical apparatus comprising a target, means for generating a beam of charged particles and for projecting said beam against said target, means for deflecting said beam away from said target in response to a quantity to be measured, an impedance unit, means for conducting said charged particles away from said target through said unit and means, including a timing element, for measuring said quantity, said timing element

being responsive to the voltage drop across said impedance unit.

7. Electrical apparatus comprising means for generating a beam of electrons, timing means for giving said beam a timing movement, a receiving chamber located in the path of said beam, means for normally preventing said beam from entering said receiving chamber, means responsive to a condition to be recorded for rendering said last-named means ineffective and for impressing a varying voltage upon said timing means.

8. Electrical apparatus comprising a target, means for generating a beam of charged particles and for projecting said beam against said target, means for deflecting said beam in accordance with a quantity to be measured and for deflecting said beam away from said target in response to said quantity, means for storing a quantity of electrical energy during the time said beam is striking said target, means for discharging said energy at a predetermined rate the instant that said beam is deflected from said target and means for deflecting said beam in accordance with said discharge.

9. Electrical apparatus comprising a target, means for generating a beam of charged particles and for projecting said beam against said target, means for deflecting said beam away from said target, means for storing a quantity of electrical energy during the time said beam is striking said target and means for discharging said energy at a predetermined rate the instant that said beam is deflected from said target.

10. Electrical apparatus comprising a target, means for generating a beam of charged particles and for projecting said beam against said target, means for deflecting said beam away from said target, means for storing a quantity of electrical energy during the time said beam is striking said target, means for discharging said energy at a predetermined rate the instant that said beam is deflected from said target and a work circuit so connected that it is actuated in accordance with said discharge.

11. Electrical apparatus comprising a target, means for generating a beam of charged particles and for projecting said beam against said target, means for deflecting said beam away from said target, means for storing a quantity of electrical energy during the time said beam is striking said target, means for discharging said energy at a predetermined rate the instant that said beam is deflected from said target and means for deflecting a beam of charged particles in accordance with said discharge.

12. Electrical apparatus comprising means for generating a beam of charged particles, a target positioned in the normal path of said particles, means, including an impedance element, for carrying said particles

away from said target, a work circuit connected in shunt to said impedance element and means for deflecting said beam of electrons away from said target.

13. Electrical apparatus comprising means for generating a beam of charged particles, a target positioned in the normal path of said particles, means, including a resistance unit, for carrying said particles away from said target, a condenser connected in parallel with said resistance unit whereby a parallel circuit is formed, a work circuit connected across at least a portion of said parallel circuit and means for deflecting said beam of charged particles away from said target.

14. Electrical apparatus comprising means for generating a beam of charged particles, a target, means for projecting said beam against said target, means for deflecting said beam away from said target and means for conducting said charged particles away from said target and for deflecting a beam of charged particles in response to said first-named deflection.

15. Electrical apparatus comprising a resistance unit, and electrostatic timing plates, said resistance and plates being connected in parallel, one end of said unit being connected to a target, means for projecting a beam of charged particles against said target and means for deflecting said beam away from said target in response to a quantity to be measured.

16. Electrical apparatus comprising means for generating an electron beam, a resistance, means shunted across at least a portion of said resistance for deflecting said electron beam, means for maintaining a continuous flow of current through said resistance and means for interrupting said continuous flow in response to a quantity to be measured.

17. Electrical apparatus comprising means for generating an electron beam, a condenser, a resistance shunted across said condenser, means shunted across at least a portion of said resistance for deflecting said electron beam, means for maintaining a continuous flow of current through said resistance and means for interrupting said continuous flow in response to a quantity to be measured.

In testimony whereof, I have hereunto subscribed my name this 17th day of June, 1929.

OTTO ACKERMANN.
